Primary Examiner — Prabhakar Deshmukh(74) *Attorney, Agent, or Firm* — Lawrence S. Cohen(57) **CLAIM**

I claim the ornamental design for multi-access bike lock, as shown and described.

DESCRIPTION

FIG. 1 is a perspective view of a multi-access bike lock showing my new design;

FIG. 2 is a front elevational view thereof the rear elevational view being the same;

FIG. 3 is a bottom view thereof the top view being the same;

FIG. 4 is a right side view thereof the left side view being the same;

FIG. 5 is a perspective view of a second embodiment of a multi-access bike lock;

FIG. 6 is a front elevational view thereof the rear elevational view being the same;

FIG. 7 is a bottom view thereof the top view being the same;

FIG. 8 is a right side view thereof the left side view being the same;

FIG. 9 is perspective view of a third embodiment of a multi-access bike lock;

FIG. 10 is a front elevational view thereof the rear elevational view being the same;

FIG. 11 is a bottom view thereof;

FIG. 12 is a top view thereof; and,

FIG. 13 is a right side view thereof the left side view being the same.

The broken lines indicate unclaimed portions and form no part of the claimed design.
